United States Patent

Des. 238,211

Patented Dec. 23, 1975

238,211

COMBINED HAIR CURLING IRONS AND HEATING UNIT THEREFOR

Robert S. Waters and Meyric K. Rogers, Lancaster, Pa.,
assignors to Schick, Incorporated, Los Angeles, Calif.

Filed June 24, 1974, Ser. No. 482,021

Term of patent 14 years

Int. Cl. D28—03

U.S. Cl. D86—10 E

FIG. 1.

FIG. 2.

FIG. 3.

FIG. 4.

FIG. 5.

FIG. 1 is a perspective view of a combined hair curling irons and heating unit therefor showing our new design;

FIG. 2 is a right side elevational view of FIG. 1;

FIG. 3 is a top plan view of FIG. 1;

FIG. 4 is a front elevational view of FIG. 1;

FIG. 5 is a rear elevational view; and

FIG. 6 is a bottom plan view.

The conventional power cord is shown fragmentarily for convenience of illustration.

The left side elevational view of the combined hair curling irons and heating unit therefor is a mirror image of the right side elevational view shown in FIG. 2.

We claim:

The ornamental design for a combined hair curling irons and heating unit therefor, as shown and described.
